UNITED STATES PATENT OFFICE.

FREDERICK JOHN G. MAISENHALDER, OF BALTIMORE, MARYLAND, ASSIGNOR TO
MARYLAND METAL BUILDING COMPANY, INC., A CORPORATION.

SHEET-METAL BUILDING.

1,427,007.

Specification of Letters Patent. Patented Aug. 22, 1922.

Application filed December 22, 1920. Serial No. 432,504.

To all whom it may concern:

Be it known that I, FREDERICK JOHN G. MAISENHALDER, a citizen of the United States, residing at Baltimore, in the city 5 of Baltimore and State of Maryland, have invented certain new and useful Improvements in a Sheet-Metal Building; and I do hereby declare the following to be a full, clear, and exact description of the invention, such as will enable others skilled in the 10 art to which it appertains to make and use the same.

The object of the invention is to provide a simple and comparatively inexpensive 15 construction of sheet metal building adapted for manufacture in sections or units at a central distributing point such as a factory and transportation to the point of use in condition for assembling under such 20 conditions as to minimize the risk of distortion or damage in transit; and furthermore to provide a construction of units or elements facilitating the assembling thereof without the employment of either a temporary 25 or permanent frame work under such conditions as to insure a stable water proof structure capable of resisting the tendency of its own or applied weight or wind pressure to distort or disarrange the parts or 30 members thereof, and moreover to provide a structure having a neat and ornamental appearance adapting it for use either as a garage or for dwelling purposes and either for temporary or permanent use; and with 35 these objects in view the invention consists in a construction, combination and relation of parts of which a preferred embodiment is shown in the accompanying drawings, wherein:

40 Figure 1 is a side view, and

Figure 2 is an end view, partly broken away of a building embodying the invention.

Figure 3 is a detail sectional view of one 45 of the wall panels or units.

Figure 4 is an enlarged detail section showing the joints between two wall panels or units.

Figure 5 is a sectional view similar to 50 Figure 4 of the connected edges of two roof panels or units.

Figure 6 is a detail section of a corner panel or unit.

The wall and roof panels or units 10 and 55 11 are of similar construction and obviously

may be made of any desired length to suit the dimensions of the proposed structure, and they are preferably made in stock widths as for example twenty-four inches (although obviously this may be varied at 60 will), each panel or unit being provided with longitudinal oppositely, or inwardly and outwardly, directed ribs or offsets 12 and 13 which are preferably cross sectionally angular as shown to represent for example one-half of a hexagon, to the end that the faces of each rib or corrugation are of equal width and the side faces converge toward the projecting or surface face which is parallel with the plane of the panel or 70 unit.

The corner panels or units are preferably constructed to continuously span the angle of the structure so as to present an unbroken surface, and to this end a blank 75 such as is employed to form a wall section or unit is folded upon itself at its longitudinal center to form the angle 14, such a corner panel or unit being indicated at 15 and shown in detail in Fig. 6. 80

The joints at the adjacent edges of the panels or units, which, contrary to the usual practice in the construction of sheet metal buildings, are not overlapped and hence are not open to the objection of involving a waste of wall material, are provided by forming triangular beads 16, directed inwardly at the edges of the panels or units, or the sheets constituting such panels or units, each bead having a wall 17 90 perpendicular to the general plane of the panel or unit and a wall 18 disposed at an acute angle to the plane of the wall 17 with its free edge terminating short of the plane of the body portion of the sheet forming 95 the panel or unit as indicated in Figures 4 and 5, the joints between the panels or units of the side wall and roof corresponding in construction. The triangular beads at the adjacent edges of two panels or units 100 are cross sectionally of right angled triangular form to provide for arranging the altitude sides of the beads of two adjoining panels or units in close relation as shown in Figures 4 and 5, so that the adjacent beads on the adjoining panels combine to form an isosceles triangle, and said adjacent beads are then housed in a cap 20 of cross sectionally isosceles triangular form, constructed of a strip of metal folded 105 110

at its longitudinal center to form the acute angle, which however is preferably rounded as shown in Figures 4 and 5 with the extremities of the strip or blank folded inward to constitute the base of the triangle,— such base elements or flanges 21 being extended under the free edges of the walls 18 of the beads 16 and terminating close to the perpendicular or altitude walls 17 of the 10 said right angled triangular beads 16.

The effect of this construction of joint is to allow for the necessary movement to compensate for expansion and contraction incident to changes in temperature while affording a weather tight joint, effectually preventing moisture from gaining access to the interior of the wall or roof, and even should moisture gain access to the interiors of the beads, it is promptly removed therefrom by evaporation due to the fact that the beads are terminally open to permit of a free circulation of air therethrough. Furthermore, as indicated the joints are located in the cavities of the corrugations of the 25 panels or units so as not to afford projections from the general plane of the wall of the structure. Both the beads and the caps by which they are engaged and which have an interlocking relation necessitating the application of the caps by longitudinal sliding movement, are of transversely yielding construction, or in other words are transversely capable of expansion and contraction, and due to the resilience of the material are capable of a yielding movement which insures a tight joint which however is adaptable to the strains applied thereto without involving the risk of disarrangement or permanent distortion. 30 Furthermore the described construction of bead is of advantage and is preferred because of the fact that in the transportation of the panels or units from the factory to the place at which the building is to be 35 erected, such beads are less likely to be distorted or bent and thus rendered inopera-

tive. They are adapted to yield to pressure without receiving permanent bend, owing to the fact that the edges of the walls thereof are free, and moreover they are protected by the adjacent portions of the panels or units, or the corrugations which are located adjacent thereto. 50

Having thus described the invention, what I claim is:—

1. A joint construction for sheet metal building panels consisting of complementary panels having beads with outwardly extending portions in contact with each other, inwardly extending angularly disposed portions on said beads spaced from the first mentioned portions at the inner end, and a cap to intimately contact with and enclose said beads having inturned flanges insertible beneath the inner edges of the second 60 mentioned portions and in contact with the panels in advance of the first mentioned portions.

2. A joint construction for sheet metal building panels consisting of complementary panels having beads with outwardly extending portions in contact with each other, inwardly extending angularly disposed portions on said beads spaced from the first mentioned portions at the inner end, and a 70 cap to intimately contact with and enclose said beads having inturned flanges insertible beneath the inner edges of the second mentioned portions and in contact with the panels in advance of the first mentioned portions, said second mentioned portions terminating short of the panels to facilitate insertion of said flanges, and said flanges terminating short of the first mentioned portions. 80

In testimony whereof I affix my signature in presence of two witnesses.

FREDERICK JOHN G. MAISENHALDER.
